UNITED STATES PATENT OFFICE

EINER WILLIAM LARSEN, OF CHICAGO, ILLINOIS, ASSIGNOR TO WESTERN ELECTRIC COMPANY, INCORPORATED, OF NEW YORK, N. Y., A CORPORATION OF NEW YORK

FEEDING MECHANISM

Application filed April 13, 1927. Serial No. 183,330.

This invention relates to feeding mechanisms, and more particularly to improvements in mechanisms for feeding or advancing articles of circular cross section.

5 The principal object of the invention is the provision of simple, inexpensive and efficient mechanism for successively advancing articles to a predetermined position from a supply thereof.

10 In accordance with the general features of the invention, there is provided in one embodiment thereof a mechanism for automatically feeding tubular or cylindrical articles of various lengths to a centerless grinder. The articles are placed in a substantially V-shaped hopper or magazine and as they gravitate toward the open bottom end thereof they are engaged by a plurality of rotating friction disks whereby they are 15 rolled downwardly along a side wall of the hopper and caused to drop upon a continuously moving belt which serves to advance them into a funnel or tubular guide member through which they are advanced to the 20 grinding machine by a stream of water or other fluid under pressure.

Other features and advantages of the invention will become apparent in the following detailed description, reference being 25 had to the accompanying drawings, wherein

Fig. 1 is a plan view of a feeding mechanism embodying the features of the present invention, showing also a portion of a centerless grinder with which the feeding mechanism may be employed;

Fig. 2 is a front elevational view of the mechanism shown in Fig. 1;

Fig. 3 is an enlarged vertical section taken on line 3—3 of Fig. 2;

40 Fig. 4 is an enlarged fragmentary horizontal section taken on line 4—4 of Fig. 2, and

Fig. 5 is an enlarged detailed section taken on line 5—5 of Fig. 2.

45 Referring now to the drawings in detail, the numeral 10 indicates a portion of the supporting frame of a centerless grinder of any well known construction comprising a grinding wheel 11 and a peripherally opposed feeding wheel 12, the axis of the feed-

ing wheel being disposed at an angle to the axis of the grinding wheel in order to effect an automatic axial feed or traverse of the article being ground. Positioned between the grinding and feeding wheels is a horizontally disposed work rest 13 which serves to support the articles during the grinding operation. Grinding machines of this general construction are well known in the art and inasmuch as the present invention is 55 not concerned with the structural details of the grinding machine proper, further illustration and description thereof are believed to be unnecessary.

50 In accordance with the features of the present invention, mechanism is provided for successively advancing articles to be ground from a supply thereof to a position wherein they are operatively engaged by the grinding and feeding wheels. Secured to 55 the frame 10 of the grinding machine is a bracket 15 which supports a horizontally disposed channel member 16, the latter comprising the main supporting member for the improved feeding mechanism. Supported 60 at one end of the channel member 16 is a housing 18 and mounted at the opposite end thereof are a pair of vertical brackets 19 and 20. A substantially V-shaped hopper or magazine 21 for containing a plurality 65 of articles 22 to be ground is mounted between horizontally disposed parallel bars 23 and 24. One end of these bars are supported in the brackets 19 and 20, respectively, and the opposite ends thereof are supported in the housing 16. The hopper 21 is secured to the bars 23 and 24 by means of a plurality of clamping members 25—25 secured to the walls 26 and 27 of the hopper. 70

75 The lower portions of the walls 26 and 27 of the hopper are spaced from each other so as to provide an opening (Fig. 3) through which the articles are passed, one at a time, and caused to drop upon a continuously moving belt 30 which is arranged to travel 80 around a pair of pulleys 31 and 32 rotatably supported at opposite ends of the channel member 16. The pulley 32 is driven from a horizontally disposed shaft 33 by a pair of intermeshing bevel gears 34 and 35 (Fig. 4), 85 90 95 100

and the shaft 33 is, in turn, driven from a main drive shaft 37 through a pair of intermeshing bevel gears 38 and 39. The drive shaft 37 may be driven from any suitable source of power (not shown).

- A portion of the wall 26 of the hopper is cut away as indicated at 41 (Fig. 2), whereby a pair of friction rollers or circular disks 42-42 are arranged to peripherally engage the lowermost articles in the hopper. The rollers 42 are secured to a horizontally disposed shaft 44 rotatably journaled in suitable bearings formed in the housing 18 and bracket 19. By means of suitable gearing 45 connecting the shafts 33 and 44, the rollers 42 are driven at the desired predetermined speed in the direction indicated by the arrow (Fig. 3). The rollers 42 are movable longitudinally along the shaft 44 so that the distance between them may be varied in accordance with the size, stiffness or other characteristics of the articles being advanced thereby.

As the articles gravitate toward the bottom of the hopper 21, they are gripped between the rollers 42 and the curved lower portion of the wall 27, and due to the rotation of the rollers 42 the articles are rolled downwardly along the wall 27. Upon the lowermost article reaching the lower extremity of the wall 27, it falls upon the traveling belt 30. A bar 46 supported by brackets 47-47 secured to the channel member 16 serves to guide the articles as they are advanced by the traveling belt 30 into a funnel mouthed tubular guide member 48 (Fig. 5) positioned between the end of the traveling belt and the work rest 13.

As shown in Fig. 5, the guide member 48 is provided with a longitudinal opening 49 for the passage of an article therethrough, the forward end of this opening being enlarged and tapered as indicated at 50 to facilitate the entrance of the article therein. Surrounding the opening 49 and communicating therewith is a passage 52 which is disposed at an angle to the opening 49. The passage 52 is connected to a source of water or other fluid under pressure by means of suitable piping, a portion of which is indicated at 54.

In the operation of the above described mechanism, a supply of tubes 22 or other articles to be ground are placed in the hopper 21 in a horizontal position, as shown in the drawings. As the tubes gravitate toward the bottom of the hopper, they are pinched between the rotating rollers 42 and the wall 27 of the hopper and are thus rolled downwardly. Upon the lowermost tube reaching the lower extremity of the wall 27, it falls upon the continuously moving belt 30 which advances it into the tubular guide member 48 through which it is advanced to the grinding machine by the pres-

sure of the water passing through the passage 52, as hereinbefore described. As soon as the forward end of a tube reaches the grinding wheel it is carried along the grinding surface thereof by the action of the grinding and feeding wheels. It should be understood, of course, that the speed at which the rollers 42 and the belt 30 are driven depends upon the time required for the grinding operation, it being obvious that the tubes should not be advanced to the grinding wheel faster than the speed at which the grinding operation is performed. Furthermore, the rollers 42 are driven at such a speed as will insure the delivery of a tube to the belt 30 as soon as the rear end of the preceding tube has cleared the forward end of the next adjacent tube.

Although the invention as herein illustrated and described may be employed to advantage for feeding articles to a centerless grinder, it should be understood that the novel features of the invention are capable of other applications within the scope of the appended claims.

What is claimed is:

1. In a mechanism for feeding articles to a grinding machine, a traveling belt for receiving and advancing an article, a member having a passage therein for guiding the article from the discharge end of the belt to the grinding machine, and means including a passage communicating with the guide passage for directing a fluid under pressure to the surface of the article to advance it through said passage.

2. In a mechanism for advancing an article to a predetermined position, a hopper for containing a supply of articles, a continuous belt for receiving an article from the hopper, means for moving the belt to advance the article, a member having a passage therein for guiding the article from the discharge end of the belt to the predetermined position, and means including a passage terminating within the guide passage for directing a fluid under pressure to the surface of the article to advance it through said passage.

3. In a mechanism for feeding articles to a grinding machine, a continuously moving belt for advancing an article, means for guiding the article as it is advanced by said belt, a substantially V-shaped hopper for containing a supply of articles, said hopper having an opening at the bottom end thereof for the passage of articles therefrom, a plurality of driven friction rollers for successively transferring articles from the hopper to the belt, a member having a passage therein for guiding an article from the discharge end of the belt to the grinding machine, and means for directing a fluid under pressure upon the article at an angle to the

direction of its movement through said passage.

4. In an article feeding mechanism, a member having an opening therein, means for advancing an article to said opening, and means including a passage communicating with the opening for directing a fluid under pressure against a surface of the article to advance it through said opening.

5. In an article feeding mechanism, a member having an opening therein, means for advancing an article to said opening, means including a passage terminating within the opening for directing a fluid under pressure against a surface of the article to advance it through said opening, and means for delivering articles to the first mentioned advancing means.

10 6. In an article feeding mechanism, a member having an opening therein, an endless conveyor for advancing articles to said opening, and means including a passage terminating within the opening for directing a fluid under pressure against a surface of the article to advance it through said opening.

15 In witness whereof, I hereunto subscribe my name this 30th day of March, A. D. 1927.

EINER WILLIAM LARSEN.
